(57) **CLAIM**

I claim the ornamental design for a modular bird feeder, as shown and described.

DESCRIPTION

FIG. 1 is a left, top perspective view of a modular bird feeder;

FIG. 2 is a front elevational view thereof;

FIG. 3 is a top plan view thereof;

FIG. 4 is a bottom plan view thereof;

FIG. 5 is a left side elevational view thereof;

FIG. 6 is a right side elevational view thereof;

FIG. 7 is a rear elevational view thereof;

FIG. 8 is a left, top perspective, exploded view of the modular bird feeder of FIG. 1;

FIG. 9 is a front elevational view of the upper component of the modular bird feeder of FIG. 1, shown separately for clarity;

FIG. 10 is a top plan view thereof;

FIG. 11 is a bottom plan view thereof;

FIG. 12 is a left side elevational view thereof;

FIG. 13 is a right side elevational view thereof;

FIG. 14 is a rear elevational view thereof;

FIG. 15 is a front elevational view of the lower component of the modular bird feeder of FIG. 1, shown separately for clarity;

FIG. 16 is a top plan view thereof;

FIG. 17 is a bottom plan view thereof;

FIG. 18 is a left side elevational view thereof;

FIG. 19 is a right side elevational view thereof; and,

FIG. 20 is a rear elevational view thereof.

The exemplary broken line elements are for illustrative purposes only and form no part of the claimed design.
